Filed May 5, 1961, Ser. No. 108,050

Claims priority, application Germany May 25, 1960
 4 Claims. (Cl. 22—79)

The invention relates to continuous or semicontinuous metal casting, and relates more particularly to distributing means and methods for the molten metal that is subsequently solidified.

Semi-finished products made of aluminum or aluminum alloys, to which subsequently there is imparted a decorative anodic oxydation or anodic polishing, require a high degree of fineness and uniformity of grain structure. While the specific degree of fineness may to a certain extent be influenced by the handling during the preparation of the metal and subsequent forging or other hot or cold working, the degree of fineness, however, is also influenced by the conditions that prevail during or just before the solidification of the metal.

In the endeavor to improve the fineness and uniformity of the metal grains, certain attempts have been made in the past to control the flow of liquid metal into the feeding head; in all of these attempts, however, the metal flowing into the metal bath was guided along straight paths which resulted in grain structures which were not sufficiently uniformly fine as desired for decorative anodic oxydation or anodic polishing.

The instant invention provides for improvements which include that a distribution is made with a distributor in which the depth of the sump in the continuous casting die or mold is kept small and wherein the molten metal receives an angular momentum before it flows into the metal bath.

It is accordingly among the principal objects of the invention to provide for a method and means to improve the conditions before solidification of molten metal, by controlling the flow of the liquid metal into the feeding head and to impart a pre-determined spinning movement to the liquid metal prior to its discharge into said feeding head.

It is another object of the invention to discharge molten metal into the metal bath in the form of several streams flowing in various directions.

It is a further object of the invention to impart an angular momentum to the molten metal flowing into a metal bath.

It is still a further object of the invention to provide for means that will impart such angular momentum to the flowing molten metal.

It is another object of the invention to provide means to keep the depth of the sump in the die during the flow at a small height.

Further objects and advantages of the invention will be set forth in part in the following specification and in part will be obvious therefrom without being specifically referred to, the same being realized and attained as pointed out in the claims hereof.

With the above and other objects of the invention in view, the invention consists in the novel methods, construction, arrangement and combination of various devices, elements and parts, as set forth in the claims hereof, certain embodiments of the same being illustrated in the accompanying drawings and described in the specification.

The foregoing and other objects of the invention will be best understood from the following description of one exemplification thereof, reference being had to the accompanying drawings, wherein:

2

FIG. 1 is a fragmentary plan view showing a distributor in a metal bath held in a continuous casting die or mold in accordance with an embodiment of the invention; and

FIG. 2 is a fragmentary sectional view taken on the line 2—2 of FIG. 1.

In carrying the invention into effect in one of the embodiments which has been selected for illustration in the accompanying drawings and for description in this specification, there is provided a distributor such as a bucket 1 that is held at one end of a balancing beam 3. The beam 3 carries at the other end an adjustably positionable counterbalance weight 4. To the beam 3 there is furthermore connected an arcuate rod 3a that carries float means such as two floats 2. The beam 3 includes a knife edge 5.

The bucket 1 is partially immersed in the bath of molten metal 6a that is held in the mold 6. A tapered metal discharge nozzle 7 is provided that extends vertically and has a substantially horizontal opening 7a.

The assembly of the bucket 1, the beam 3, the weight 4, and the floats 2 is supported by the floats 2 swimming on the surface of the metal bath 6a, and by the beam 3 resting with the knife edge 5 on the upper surface of the wall of the mold 6.

The operator, at the start of the casting, will adjust the weight 4 on the beam 3 to such a position that the bucket 1 floats on the surface of the metal bath 6a in a predetermined position below the discharge nozzle 7; in this predetermined position the bottom 12 of the bucket 1 is disposed but for a small distance below the opening 7a, thereby defining with the lower end of the nozzle 7 a circular vertical gap and guiding the molten metal to flow horizontally, through said gap, between the opening 7a and the bottom 12 of the bucket 1 after it leaves the nozzle opening 7a. The bucket regulates in a well-known manner the flow of the metal through the nozzle 7 in that in accordance with the variations in the height of the level 9 of the metal bath 6a in the mold 6, the said gap is varied in height and thereby the flow through the opening 7a of the nozzle 7 is more or less restricted by the bucket 1.

The bucket 1 has upright slots 8 through which the metal pours out until it reaches a freezing zone near the sidewall of the mold 6. The slots 8 are preferably V-shaped, and extend throughout from the bottom 12 to the top edge of the sidewall 11 of the bucket 1; by this arrangement, the metal streams will exit from the bucket mainly in oblique upward direction out to the sump center.

In accordance with a preferred embodiment, the sidewall 11 of the bucket 1 is so arranged that the terminal surfaces 10a and 10b of the V-slots are inclined relative to the radial direction from the center of the buck bottom 12. By this arrangement, the portions of the sidewall 11 between the slots 8 are spirally off-set relative to the center of the bottom 12.

Due to this structure, there will be imparted to the molten metal exiting from the bucket 1 an angular momentum or spinning, as indicated by the arrow C in FIG. 1. This arrangement of the bucket permits an excellent utilization of the kinetic energy of the molten metal discharged by the nozzle 7, so that there is assured a strong movement of the molten metal in the feeding head.

The inner diameter A of the bucket bottom 12 is the same as, or only slightly larger than, the external outer diameter E of the bottom portion of the nozzle 7, and the side wall 11 of the bucket 1 is tapered internally similar to the external taper of the nozzle 7.

In accordance with the invention, the molten metal flows through the slots 8 out of the bucket 1 in the direction towards the wall of the mold 6. The metal flows out of the bucket in strong streams and causes a forceful

movement since the kinetic energy of the molten metal flowing out of the nozzle 7 is, owing to the close fit of the bucket 1 relative to the nozzle 7, preserved. The close fit on the other hand promotes guiding of the bucket 1 floating on the metal bath 6a.

It has been found that the aforesaid strong movement at the feeding head increases with increasing casting speed; the refinement of grain achieved thereby increases to an optimum value. Since, moreover, with the instant bucket construction the depth of the sump increases but very little with increasing casting speed, the aforesaid optimum of the achieved quality of the cast metal is attained at a high casting production.

The improved quality of the cast metal is particularly noticeable at the anodic polishing and anodic oxydation of semi-finished material which is derived by forging or other working from billets thus cast. The improved quality is, for instance, characterized by the absence of spots or stripes. The fine uniform grain structure promotes the homogeneity of hardenable alloys, and generally improves their forging or pressing qualities.

The instant invention is particularly suitable for the casting of round billets, but may also be used for billets of rectangular cross-section.

Example

For the casting of round billets with a diameter of about 6 in. to about $7\frac{3}{32}$ in., a bucket 1 is used the bottom 12 of which has a minimum diameter A of about $1\frac{1}{16}$ in., which corresponds approximately to the outer diameter E of the nozzle 7. The outermost diameter B of the sidewall 11 of the bucket 1 is about $2\frac{3}{8}$ in., and the height H of the bucket about 1 in. The nozzle 7 has an exit diameter D of about 0.315 in. With such a diameter D of the nozzle 7 there can in the said arrangement be cast round billets of about $7\frac{3}{32}$ in. diameter at a lowering speed of from about $3\frac{1}{2}$ to $4\frac{3}{4}$ in. per minute for the following aluminum alloy and temperature: aluminum alloy with from 0.4 to 0.9 percent magnesium and from 0.3 to 0.7 percent silicon and at a temperature of about 1292° F. The resulting round billets are characterized by uniform fine grain structure, and after a press operation and following anodic oxydation the articles have neither stripes nor spots.

We wish it to be understood that we do not desire to be limited to the exact details of construction shown and described, for obvious modifications will occur to a person skilled in the art.

Having thus described the invention, what we claim as new and desire to be secured by Letters Patent, is as follows:

1. A distributor, for use in connection with a molten metal bath in a walled mold for continuous casting and a nozzle having a substantially horizontal discharge opening for the passage of molten metal toward said bath, said distributor comprising a bucket including a bottom and a sidewall, support means, including float means

5 adapted to be supported on said metal bath, and a balancing beam including a counter-balancing weight and a balancing knife edge operable to rest on the mold wall, thereby supporting said bucket in a position wherein said bottom of the bucket is disposed a short distance below the discharge opening of said nozzle, said bucket having in the sidewall a series of upright slots for the discharge of molten metal from the bucket into said bath.

2. In a distributing arrangement, the combination with a walled mold for a molten metal bath and a substantially vertical discharge nozzle conveying molten metal towards said bath and comprising a lower portion of predetermined circumference defining a horizontal discharge plane, of a bucket including a bottom and a sidewall said sidewall defining an internal orbit only slightly larger than said circumference, support means, including a float

10 means supported by said bath, and a balancing beam including a counter-balancing weight and a balancing knife edge operable to rest on the mold wall, thereby suspending said bucket in a position wherein said bottom of the bucket is disposed a short distance below said discharge plane of said nozzle, said bucket having in the sidewall a series of upright slots adapted for the discharge of molten metal from the bucket into said bath.

20 3. In a distributing arrangement, as claimed in claim 2, said sidewall terminating in a top edge, said slots being V-shaped and extending throughout from the lowermost to the topmost parts of said bucket.

30 4. In a distributing arrangement, as claimed in claim 3, said slots having opposite surfaces inclined relative to the radial direction from the center of said bottom.
